KNITTED FABRIC

Robert Kirkland Mills, Sherwood, Nottingham, England, assignor to Hosiery Developments Limited, Nottingham, England

Application January 14, 1938, Serial No. 185,041
In Great Britain December 18, 1936

3 Claims. (Cl. 66—169)

This invention comprises improvements in knitted fabric and in the production thereof. More particularly the invention refers to fabric of a kind wherein, for the purpose of minimizing 5 stitch running or laddering in the event of thread breakage, locked stitches are formed in the fabric by passing a thread loop through and also around a stitch loop, the stitch-locking thread being coiled around each leg or side of the stitch loop.

10 The object of the present invention is to render the ladder-proof properties of fabric of the aforesaid kind more positive or definite, to provide the fabric with a degree of elasticity in the direction of the stitch courses which is equal to and even 15 greater than that of ordinary knitted fabric and also preserve the normal elasticity in the direction of the stitch wales, to produce a fabric which is capable of quick recovery to normal after being repeatedly stretched, and also provide a fabric 20 having a substantially smooth and even surface. Fabric possessing the combined properties as above can be knitted in fine gauges from silk or artificial silk yarn and can be employed with advantage in the production of underwear and 25 other articles of clothing; although the field of utility of the fabric is not restricted to such articles.

In practise it has been found that in fabric of the kind referred to the size or length of the 30 stitch-locking loop in relation to that of the stitch loop locked thereby has a definite and important bearing on the efficacy of the stitch-locking or run-preventing properties of the stitch. For example, should the locking loop be relatively short 35 its locking propensity is less effective than is the case when the locking loop is relatively long.

In order to elucidate this point let it be assumed that a stitch thread in the fabric is broken, thereby releasing a stitch loop from its interlinking 40 engagement with a subsequently formed loop in the same stitch wale. Now the natural tendency is for the released stitch loop to slip or to be pulled through the next previously formed loop with which same is interlinked, thereby 45 starting a run or ladder down the stitch wale; and it is the purpose of the locking loop to anchor or grip the released loop and thereby prevent or minimize the possibility of laddering. It is found, however, that if the loop of locking thread is of 50 insufficient length or size in relation to the stitch loop with which it is associated same may slip back over and through said stitch loop and thereby release same, whereas if the locking thread loop is sufficiently long or large in relation to 55 the stitch loop, said locking loop will continue

to have frictional or locking engagement with the stitch loop and will be prevented or restrained from slipping back through the stitch loop when the latter becomes tightened.

In fabric of the kind referred to as originally 5 produced, the stitch-locking loops were relatively small and embraced the stitches substantially tightly, consequently the ladder-resisting properties of the fabric were found to be unsatisfactory or uncertain, while in addition the elasticity 10 of the fabric was impaired with the result that the fabric was very liable to split or fracture in a direction at right angles to the stitch wales. Subsequent experiments proved that by introducing 15 stitch-locking thread of a length equal to or somewhat greater than the length of thread forming the stitches to be embraced thereby the requisite elasticity was imparted to the fabric; and in the specification of prior U. S. Patent No. 2,076,910 fabric of the kind referred to is described 20 wherein the amount of locking thread is increased to a degree sufficient for obtaining the required elasticity and for enabling the tension or strain applied to the fabric in the direction of the stitch courses to be shared by both 25 the stitch-forming and stitch-locking thread. This further improvement, while obtaining the desired effect as regards elasticity of the fabric and increasing its resistance to splitting in the direction of the stitch courses, has not proved 30 satisfactory as regards its ladderproof or ladder-resisting properties, and further experiments have proved that positive or definite ladder-prevention (i. e. positive stitch-locking) can only be ensured by making the stitch-locking loops appreciably longer or larger than the stitch loops. 35 Also, in order to preserve a smooth or substantially smooth surface on the fabric, the locking thread requires to be substantially evenly divided between the needle or stitch wales and the sinker 40 wales.

The present invention, therefore, resides in the provision of knitted fabric embodying locked or tied stitches of the kind referred to wherein the amount or length of thread introduced to form 45 a number of successive stitch-locking loops is substantially greater than the amount of thread introduced to form the stitches locked thereby, and wherein the length or size of a stitch-locking loop (the amount of thread in said loop) is greater 50 than the length or size of the stitch loop to be locked (the amount of thread in said stitch loop) to such an extent that, in the event of said stitch becoming released by thread breakage from its 55 interlinking engagement with another loop in the

same wale, said locking loop does not slip back completely out of locking or frictional gripping engagement with the stitch loop.

A feature of the invention also resides in the provision of knitted fabric as last described wherein the size or length of the loops of locking thread is substantially equal in the needle or stitch wales and in the sinker wales.

For the purpose of more fully describing the nature of this invention reference will now be made to the accompanying drawing wherein is illustrated a portion of fabric embodying locked or tied stitches and showing how laddering is resisted when a stitch is broken.

15 In the fabric illustrated in the drawing, each stitch loop 1 in each knitted course is locked or tied by a stitch-locking loop 2, the stitch-locking thread 2a from which the locking loops 2 are formed being finer or thinner than the stitch forming thread 1a.

At the position 3 a stitch loop has been broken, thereby releasing the previously formed stitch loop in the same stitch wale which previously depended thereon. The released stitch loop 25 which is shown pulled straight or substantially straight by virtue of lateral tension applied to the fabric, takes the form of a thread bar 4. The stitch-locking loop associated with the released stitch loop is, however, of such a relative 30 length or size that when said released stitch loop is pulled straight or substantially straight to form the bar 4 there still remains sufficient slackness in the locking thread to maintain a loop 2b, and this locking loop is maintained in engagement 35 with the thread bar 4 and becomes anchored between same and the next previously formed stitch loop 1b in the same wale, thereby preventing or resisting further stitch running down the wale.

40 In an example of the improved fabric of the type referred to, assuming that each successive stitch in a course of stitches is locked or tied as above, for every 10 inches of stitch-forming yarn 1a inserted into the fabric to produce the 45 ordinary stitch loops 1 to be locked there is at least one additional inch of stitch-locking thread 2a inserted; in other words, the amount or length of stitch thread and stitch-locking thread may be in the ratio of 10 to 11.

50 Let it be assumed for example that the fabric is produced on a 3 3/4" diameter circular knitting machine for producing stockings employing 348 needles, then the amount of stitch-forming thread introduced into a stitch course is advantageously 30 inches, and the amount of stitch-locking thread 33 1/2 inches. By so proportioning the stitch thread and stitch-locking thread it 55 will be appreciated that in the event of a stitch becoming broken there is always sufficient slack-

ness in the locking thread loop associated with the released stitch loop to prevent said stitch-locking loop from becoming straightened out and slipping clear of the loop locked thereby.

If desired, each stitch to be locked may have 5 associated with it a plurality of stitch-locking loops, e. g. two loops, each passed in a similar manner through and around the stitch loop. In other words there may be more than one locking thread 2a introduced into a course of stitches. 10

By reference to the drawing it will be seen that the loops of stitch-locking thread 2a are of substantially uniform size in the needle or stitch wales, and in the sinker wales of the fabric; in other words the stitch-locking thread is substantially evenly divided between the needle wales and the sinker wales. In consequence the elasticity of the fabric is in no way impaired, and a fabric is produced having a smooth or substantially smooth or uniform surface, that is to say 20 a surface without comparatively long plush or pile loops projecting therefrom.

I claim:—

1. A knitted fabric embodying locked or tied 25 stitches of the kind referred to wherein the amount or length of thread introduced to form a number of successive stitch-locking loops is substantially greater than the amount of thread introduced to form the stitches locked thereby, and wherein the length or size of every stitch-locking loop (the amount of thread in said loop) is greater than the length or size of the stitch loop to be locked (the amount of thread in said stitch loop) to such an extent that, in the event of said stitch loop becoming released by thread 35 breakage from its interlinking engagement with another loop in the same wale, said locking loop does not slip back completely out of locking or frictional engagement with the stitch loop.

2. Fabric according to claim 1 wherein the size 40 or length of the loops of the stitch-locking thread is substantially equal in the needle wales and in the sinker wales.

3. A knitted fabric embodying locked or tied 45 stitches of the kind referred to wherein the length or size of every stitch-locking loop is greater than that of the stitch loop with which it is associated to such an extent that in the event of said stitch loop being released from its dependent engagement with a subsequently formed stitch loop, the released loop is maintained connected with the next previously formed stitch loop in the same wale by virtue of said relatively long locking loop still retaining a looped formation and becoming anchored between the straightened or substantially straightened thread of the released stitch loop and the said next previously formed stitch loop.

ROBERT KIRKLAND MILLS.
